UNITED STATES PATENT OFFICE.

GEORGE W. BRAUNSDORF, OF NEW YORK, N. Y.

PIANO-ACTION.

1,368,107.

Specification of Letters Patent. Patented Feb. 8, 1921.

Application filed March 19, 1920. Serial No. 367,058.

To all whom it may concern:

Be it known that I, GEORGE W. BRAUNSDORF, a citizen of the United States, residing at Elmhurst, in the county of Queens, city 5 and State of New York, have invented an Improvement in Piano-Actions, of which the following is a specification.

This invention relates to the action of an upright piano and more particularly to the 10 construction of the bridle strap employed therewith and the manner of connecting the bridle strap to the bumper head. Heretofore in upright piano actions the general practice has been to permanently secure the 15 bridle strap at one end thereof to the hammer butt or the bumper head by tacking or otherwise securing the same in place permanently. This necessarily made the replacing of a broken bridle strap a difficult and un- 20 certain operation after the parts of the piano action have all been assembled. I am also aware that heretofore it has been proposed to associate one end of the bridle strap with the bumper head and its shank, slot- 25 ting the bridle strap so that the same may pass over the bumper head and surround the shank of the bumper head and thus be secured in position. This construction, however, due to the uncertainty of maintaining 30 this end of the bridle strap in place, has not been found to be entirely satisfactory and the object of my present invention is to so construct the bridle strap and to attach the same to the bumper head as to make the con- 35 nection permanent, and also one which makes the renewal of the bridle strap a com- paratively simple matter, and the construction of the parts relating to this invention will be hereinafter more particularly de- 40 scribed.

In the drawing:

Figure 1 is an elevation and partial cross section illustrating the parts of an upright piano action in which my present invention 45 is included.

Fig. 2 is a perspective view of the bumper head of the improved bridle strap attachment.

Fig. 3 is a view similar to Fig. 1 showing 50 another form of the invention.

Fig. 4 is a plan view of the bridle strap, and

Fig. 5 is a section taken on line 5—5, Fig. 4.

Referring to the drawing, 10 represents the wippen which is of the usual construction and with which there is associated the

usual jack member 11 and the ordinary hammer butt 12. With each hammer butt 12 there is a hammer spring 13 and as is also 60 customary there is associated with each hammer butt a hammer 14 which is connected thereto by a shank 15.

Each hammer butt 12 also has connected thereto a shank 16 which carries a bumper 65 head 17 adapted to contact with a stop member 18 which is supported by a shank 19 connected to the wippen 10. The parts as hereinbefore described are the ordinary members of a piano action in the type of which my 70 improved bridle strap and its connection with the bumper head may be employed. The bridle strap is indicated at 20 and as will be understood may be made of a suitable woven fabric or any other material. One 75 end of this bridle strap is attached to a plug member 21. The plug member may also be made of any suitable material and the attachment made in any desired manner, although as indicated the plug member is 80 made in halves, the parts of which are shown at 22 and 23 with the extremity of the bridle strap passed between and connected by adhesive or in any other manner to this end of the strap. The opposite end of the strap 85 may be reinforced as indicated at 24 by a strip of any suitable material and may be provided with a hole as indicated at 25 for attachment to the bridle hook. As shown in Figs. 1 and 2, an aperture 26 is provided in 90 the extension 27 of the hammer butt and is of such a diameter when made round as to receive the plug 21 so that this end of the bridle strap may be readily connected to the bumper head, and after this connection is 95 made the opposite end suitably attached to the bridle hook 28 as illustrated, making the operation of attaching the bridle strap in place a relatively easy one even after all the other parts of the action are assembled.

By reference to Fig. 3 in which the bumper head is not provided with an extension, it will be seen that in a suitable position, the bumper head may be provided with a recess 29 adapted to receive the plug member at one end of the bridle strap to secure the same in position thereon. Other than this, the structure in this figure is the same as those hereinbefore described.

I claim as my invention:

1. In an upright piano action and in combination with a hammer butt, a bumper head having an aperture therein and a shank connecting the bumper head to the hammer

- butt, a bridle strap, and a multiple part plug between the parts of which one end of the bridle strap is secured and the plug inserted in the said aperture in the bumper head.
- 5 2. In an upright piano action and in combination with a hammer butt, a bumper head having an aperture therein and a shank connecting the bumper head to the hammer butt, a bridle strap, and a two part plug,
- 10 with one end of the bridle strap secured between the parts of the plug and the plug inserted in the said aperture in the bumper head.
3. In an upright piano action and in combination with a hammer butt, a bumper head 15 having an extension provided with an aperture and a shank connecting the said bumper head to the hammer butt, a bridle strap, and a two part plug having one extremity of the bridle strap secured between the parts there- 20 of and the plug inserted in the said aperture in the extension of the bumper head.

Signed by me this 25th day of February, 1920.

GEORGE W. BRAUNSDORF.
